UNITED STATES PATENT OFFICE.

WILLIAM SZLÁNYI, OF NEW YORK, N. Y., ASSIGNOR TO CHARLES H. DIETZE, OF NEWARK, NEW JERSEY.

TOY CANNON.

1,144,739.

Specification of Letters Patent. Patented June 29, 1915.

Application filed March 5, 1915. Serial No. 12,471.

To all whom it may concern:

Be it known that I, WILLIAM SZLÁNYI, a subject of the King of Hungary, and a resident of the city of New York, in the county 5 of New York and State of New York, have invented certain new and useful Improvements in Toy Cannons, of which the following is a specification.

The present invention relates to a toy cannon, and has for one of its objects to provide a toy of this kind which discharges projectiles and simultaneously explodes or fires percussion caps, the latter being, preferably, of the paper cap type.

Another object of the invention is to produce a novel spring-actuated discharging mechanism for the projectiles, which constitutes at the same time a hammer for exploding or firing the fulminate.

A further object of the invention is to provide a toy of the character described which is simple in construction, efficient in operation, and one that can be manufactured on a commercial scale, or in other words 25 which is not so difficult to produce as to be beyond the reasonable cost of such an article.

With these and other objects in view, which will more fully appear as the nature of the invention is better understood, the 30 same consists in the combination, arrangement and construction of parts hereinafter fully described, pointed out in the appended claim and illustrated in the accompanying drawings, it being understood that many 35 changes may be made in the size and proportion of the several parts and details of construction within the scope of the appended claim without departing from the spirit or sacrificing any of the advantages of the invention.

One of the many possible embodiments of the invention is illustrated in the accompanying drawings, in which:—

Figure 1 is a vertical longitudinal section taken through a toy cannon constructed in accordance with the present invention, its parts being in position for discharging the projectiles and for firing the cap; Fig. 2 is a section taken on line 2—2 of Fig. 1; Fig. 50 3 is a section taken on line 3—3 of Fig. 1; and Fig. 4 is a rear elevation of the same.

In the drawings, the numeral 10 indicates a gun carriage, mounted upon wheels 11 and provided with a trail 12. The barrel 13 of 55 the gun is screwed or otherwise fixedly at-

tached to a frame 14, which includes two vertically extending parallel plate members 15, the latter abutting against similarly disposed plate members 16 of the trail 12. A pintle 17 extends through the plates 15 and 16, and upon the said pintle pivots the gun. This pintle is seated furthermore in a suitably shaped recess 18 in the top plate of the carriage. A pin 19, extending through holes 20 in the carriage and through one of a row 65 of holes 21 in each plate member 15, serves to fix the position of the gun upon its carriage. The rows of holes 21 in the plate members 15 are disposed on arcs, to permit of an adjustment of the cannon upon its 70 carriage.

The elements so far described may be of any suitable construction and configuration, the main thing being that they be made in the conventional form of a cannon.

Within the bore 22 of the cannon is slidably disposed an ejecting plunger 23, that is mounted upon a rearwardly extending stem 24. This stem projects through a hole 25 in the head 26 of the cannon, and is provided upon its free end with a lug 27 for a purpose hereinafter to be described. In the stem 24 is formed a recess 28, in which the upper edge of the opening 25 is adapted to be seated (Fig. 1), for holding the ejecting 85 plunger in its retracted position against the action of the firing and ejecting spring 29, the latter being coiled around the stem 24, and bearing against the plunger 23 and the head 26 of the cannon. In alignment with 90 the lug 27 is formed upon the head 26 a cap holder 30. This holder is provided in its rear end with a slot 31 into which the lug 27 of the stem is adapted to be projected by the spring 29.

To the carriage 10 is pivoted a lever 32. This lever has upon its inner end vertically extending portions 33, which extend through apertures 34 in the top plate of the gun carriage, permitting thus of a play of said 100 lever.

The projectiles may be either in the form of cylindrical bodies 35 which are adapted to be fed into the bore of the gun, or they may be in the form of balls, preferably of 105 rubber.

The operation of the toy is as follows: The stem 24 and the ejector plunger 23 carried thereby are retracted until the upper edge of the opening 25 is seated in the recess 110

28 in said stem. The gun is thus "cocked." The lever 32 is then brought into engagement with the lug 27 of the stem (Fig. 1), the play above described of the lever permitting such engagement without disengaging the upper edge of the opening 25 from the recess in said stem. A projectile is then brought into the bore of the cannon, and a paper cap into the cap holder 30. To fire 10 the piece, the lever 32 is depressed, whereby the edge of the opening 25 is unseated from the recess in the stem 24. The spring 29 becomes thus operative, whereby the plunger 23 is forcibly carried forward, striking 15 the projectile in front of it, and driving it out with considerable force. At the same time the lug 27 of the stem delivers a blow against the cap in the cap holder with a force enough to explode the fulminate.

20 What I claim is:—

In a toy cannon, the combination with a gun carriage, of a barrel pivoted thereto, means for fixing the position of said barrel

upon said carriage, said barrel having a contracted opening in its rear end, an ejecting plunger slidably disposed in said barrel, a stem carrying said plunger extending through the opening in said rear end and provided with a lug upon its free end, a cap holder upon the rear end of said barrel in alignment with said lug, a spring for forcing said plunger forward, coacting means upon said barrel and said stem for holding the latter in its retracted position, and a lever pivoted to said carriage adapted to act, at will, upon said stem for disengaging said last named means, whereby said spring is rendered operative.

Signed at New York, in the county of New York, and State of New York, this 5th day of Jan., A. D. 1915.

WILLIAM SZLÁNYI.
